(No Model.)

C. B. MATTHEWS.

HARNESS.

No. 259,184

Patented June 6, 1882.

Inventor:
Charles B. Matthews

Charles A. Pee
Frederick F. Campbell by O. Drake, Atty.
Attest.

UNITED STATES PATENT OFFICE.

CHARLES B. MATTHEWS, OF NEWARK, NEW JERSEY.

HARNESS.

SPECIFICATION forming part of Letters Patent No. 259,184, dated June 6, 1882.

Application filed April 11, 1882. (No model.)

To all whom it may concern:

Be it known that I, CHARLES B. MATTHEWS, a citizen of the United States, residing at Newark, in the county of Essex and State of New Jersey, have invented certain new and useful Improvements in Harness; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates more especially to that class of harness known as "express-harness," wherein great strength and power of resistance are required to meet the strain of the heavy loads of goods carried by the teams.

Heretofore backing-straps used in harness have been composed of leather buckled to and in the harness. Said leather is not sufficiently strong to sustain the wear and tear for any considerable time, so that often it costs as much to keep the said backing-strap in repair as the whole of the remaining portions of the harness. By my invention the backing-strap is given adequate strength, so that it will endure for a long time the great tension given to it in the process of backing the said heavy loads.

Referring to the accompanying drawings, in which similar letters of reference indicate like parts in each of the figures, Figure 1 is a plan representation of a team of horses, showing the location of the backing-straps and their relation to the other portions of the harness; and Fig. 2 is a plan showing more in detail my mode of construction.

In the drawings, *a* represents the portion of the strap adapted to engage with the pole-chain *h*, and *b b'* those portions thereof adapted to engage with the breeching *i* and receive the draft from the same in the process of backing. In constructing the said portions *a b b'*,

I form the core *d* of wire rope or metallic chains,

the ends of which form loops adapted to receive means for securing said portions to the harness and to one another. Said loops may receive loop-rings *e*, by which the wear is taken from the wire rope. The portion *a*, which engages with the pole-chain *h* or pole, is longer than the parts *b b'*, and passes behind the inner fore leg of the horse. The parts *b b'* are slightly unequal in length, so that the strain thereon will be equalized. At the junction where said portions *a b b'* meet I secure a belly-pad, *f*, adapted to lie between the portions *a b b'* and the horse's belly and prevent the action of the joints from injuring the animal. The wire rope or linked chain or other metallic core is covered by leather or other suitable covering, which protects the horses therefrom.

Having thus described my invention, what I claim is—

1. A metallic backing-strap consisting of parts *a b b'*, adapted to be secured to the harness and to the pole-strap, and to receive a portion of the strain from the horses in the process of backing a vehicle, substantially as set forth.

2. In harness, the combination, with the pole-chain or pole and the breeching *i*, of the metallic backing-strap *a b b'*, arranged and operating substantially as set forth.

3. As an improved article of manufacture, a backing-strap consisting of the parts *a b b'*, composed of the metallic core *d*, having a suitable covering, joined together at one end, and having means, as *g*, for securing the same to the horse's harness at the other, and having the belly-pad cover said portions, substantially as and for the purposes set forth.

In testimony that I claim the foregoing I have hereunto set my hand this 16th day of March, 1882.

CHAS. B. MATTHEWS.
